UNITED STATES PATENT OFFICE.

ROBERT J. DARBY, OF TROUPE, TEXAS, ASSIGNOR OF ONE-HALF TO
GEORGE W. SHAW, OF SAME PLACE.

DESIGN FOR A COLTER-BRACE.

SPECIFICATION forming part of Design No. 27,391, dated July 20, 1897.

Application filed June 3, 1897. Serial No. 639,349. Term of patent 14 years.

To all whom it may concern:

Be it known that I, ROBERT J. DARBY, a citizen of the United States, residing at Troup, in the county of Smith and State of Texas, 5 have invented and produced a certain new and original Design for Colter-Braces; and I do declare the following to be a full, clear, and exact description of the invention, such as will enable others skilled in the art to which 10 it appertains to make and use the same.

My invention has relation to a new and original design for colter-braces for plows; and it consists of a design of this character of 15 in the accompanying drawing, in which I have illustrated the invention in perspective.

The leading feature of my design consists

in a flat metallic strip approximately U shape in outline, the limb A being of less length than the limb B and each provided with an 20 elongated head C, projecting laterally and lying in the same plane as the faces of the limbs, and each provided with an ornamental disk-like knob.

What I claim as my invention is—

The design for a colter-brace, as herein shown and described.

In testimony whereof I hereunto affix my signature in presence of two witnesses.

ROBERT J. DARBY.
